UNITED STATES PATENT OFFICE.

WILLIAM P. HAMMOND, OF PASSAIC, NEW JERSEY.

CONNECTOR.

1,044,885.

Specification of Letters Patent.

Patented Nov. 19, 1912.

Application filed November 4, 1911. Serial No. 658,557.

To all whom it may concern:

Be it known that I, WILLIAM P. HAMMOND, citizen of the United States, residing at Passaic, in the county of Passaic and 5 State of New Jersey, have invented certain new and useful Improvements in Connectors, of which the following is a specification.

The present invention relates to certain new and useful improvements in the construction of connectors or clips such as are 10 frequently employed for securing wires or conductors to the binding post of a battery or spark plug, or some similar member.

One of the objects of the invention is to 15 provide a connector which is comparatively simple and inexpensive in its construction, which can be quickly applied to a binding post or detached therefrom, and which embodies novel features of construction where- 20 by a good electrical connection is established with the binding post or other similar member to which the connector is applied.

With these and other objects in view, the 25 invention consists in certain novel combinations and arrangements of the parts as will more fully appear as the description proceeds, the novel features thereof being pointed out in the appended claims.

For a full understanding of the invention, reference is to be had to the following 30 description and accompanying drawing, in which:

Figure 1 is a perspective view of a connector constructed in accordance with the invention. Fig. 2 is a bottom plan view of the connector, the two gripping rings or washers being shown as forced inwardly by the fingers so as to bring the openings thereof into registry with each other. Fig. 3 is a sectional view showing the connector as applied to a binding post. Fig. 4 is a transverse sectional view through the connector, and Fig. 5 is a longitudinal sectional view on the line 5—5 of Fig. 2.

Corresponding and like parts are referred to in the following description and indicated in all the views of the drawings by the same reference characters.

Specifically describing the embodiment of the invention illustrated by the accompanying drawings, the numeral 1 designates the stock or body portion of the connector, one end thereof being formed with a notch 2 adapted to bear against the binding post or like member to which the connector is applied, while the opposite end of the stock

is formed with lateral ears which are bent inwardly to provide a sleeve 3 adapted to engage a wire or conductor 4. The notched end of the stock 1 is formed with laterally extending spring arms 5 which are returned upon themselves and terminate in perforated plates or washers 6 which are adapted to slide over each other. The openings or perforations 7 of the said plates are normally out of alinement with each other, as indicated by Figs. 1 and 4 of the drawing, although by pressing inwardly upon the returned portions of the arms 5, the openings 7 of the two plates may be brought into registry with each other, as indicated by Fig. 2. The connector may then be applied to a binding post 8 or similar member in the usual manner and the spring arms 5 released so as to cause the perforated plates 6 to grip 75 the binding post. The notch or seat 2 is also adapted to engage one side of the binding post, and it will be observed that this notch is arranged out of alinement with the openings 7 so as to hold the connector in an 80 inclined position with respect to the axis of the binding post. The binding post is thus engaged at two separate and distinct points, and any outward pull by the wire or conductor 4 will tend to throw the seat 85 2 more securely against the binding post and also to draw the perforated plates 6 into a better engagement therewith. This connector or clip can be readily formed from a single piece of sheet material and can be 90 very quickly applied to a binding post or detached therefrom. It will also be obvious that owing to the provision of the seat 2 and the peculiar arrangement thereof with respect to the perforated plates or jaws 6, a 95 good electrical connection between the members will always be assured.

Having thus described the invention, what I claim as new and desire to secure by Letters Patent, is:—

1. A connector including a stock provided with a seat adapted to bear against the binding post, and post gripping members carried by the stock and offset from the plane thereof.

2. A connector including a stock formed with a seat adapted to bear against a post, and a pair of cooperating spring actuated jaws carried by the stock and offset from the plane thereof, the said jaws being adapted to positively engage the post.

3. A connector including a stock formed

100

110

with a seat adapted to engage one side of a post, and spring arms projecting from the stock and terminating in post engaging members adapted to coöperate with each other to grip the post.

4. A connector including a stock provided with a seat adapted to engage a post, the said stock being provided with laterally projecting spring arms which are returned 10 and terminate in perforated plates adapted to coöperate with each other to grip the post.

5. A connector including a stock provided with a notched seat adapted to bear loosely 15 against one side of a post, the said stock being formed with laterally projecting spring arms which are returned and terminate in overlapping plates having cut away portions adapted to coöperate with each 20 other to positively grip the post.

6. A connector including a stock provided with a notched seat adapted to bear loosely against one side of a post, the said stock being formed with laterally projecting 25 spring arms which are returned and terminate in overlapping plates arranged in a spaced relation to the stock and having cut away portions adapted to grip the post, the

said cut away portions of the overlapping plates and the notched seat having such a 30 relation to each other as to hold the connector at an inclination to the axis of the post.

7. A connector including a stock formed with a notched seat adapted to bear loosely 35 against one side of a post, the said stock being also provided with means for engaging a conductor, spring arms projecting laterally from the stock and having the ends thereof returned and terminating in 40 overlapping perforated plates having a spaced relation to the stock, the spring action of the arms causing the perforated plates to grip the post when the connector is applied thereto and the perforations of 45 the plates and the notched seats being out of alignment with each other so as to hold the connector at an inclination to the axis of the post.

In testimony whereof I affix my signature in presence of two witnesses.

WILLIAM P. HAMMOND.
